[57] CLAIM

The ornamental design for a weed puller, as shown and described.

DESCRIPTION

FIG. 1 is a front and right side perspective view of a weed puller, showing my new design;

FIG. 2 is an enlarged front and right side perspective view of the lower part thereof being shown broken-away to indicate a partial view;

FIG. 3 is a front elevation view thereof;

FIG. 4 is a right side elevation view thereof with the left side elevation view being a mirror image; and,

FIG. 5 is a rear elevation view thereof.
